UNITED STATES PATENT OFFICE

156,021

DESIGN FOR A CREAM SEPARATOR

Joseph W. Manks, Edmonds, Wash.

Application May 20, 1947, Serial No. 139,161

Term of patent 3½ years

(Cl. D23—1)

To all whom it may concern:

Be it known that I, Joseph W. Manks, a citizen of the United States, residing at Edmonds, in the county of Snohomish and State of Washington, have invented a new, original, and ornamental Design for a Cream Separator, of which the following is a specification, reference being had to the accompanying drawing, forming part thereof.

I claim:

The ornamental design for a cream separator, substantially as shown.

JOSEPH W. MANKS.
